STRINGED MUSICAL INSTRUMENT

Paul Daniel Broussard, Andrew, La.
(Rte. 2, Box 271, Kaplan, La. 70548)

Filed Apr. 29, 1968, Ser. No. 11,690

Term of patent 14 years

Int. Cl. D17—03
U.S. Cl. D56—1

I claim:

The ornamental design for a stringed musical instrument, substantially as shown.
